UNITED STATES PATENT OFFICE.

ROBERT E. L. GRAY, OF TORNADO, WEST VIRGINIA.

EGG-CRATE.

SPECIFICATION forming part of Letters Patent No. 617,011, dated January 3, 1899.

Application filed April 26, 1898. Serial No. 678,870. (No model.)

To all whom it may concern:

Be it known that I, ROBERT E. L. GRAY, a citizen of the United States of America, and a resident of Tornado, county of Kanawha, 5 State of West Virginia, have invented certain new and useful Improvements in Egg-Crates, of which the following is a specification.

The object of my invention is to provide an egg-crate which will prevent breakage of the 10 eggs during transportation.

The nature of my invention will be described below, and pointed out in the claim.

In the drawings, Figure 1 is a plan view, the cover partly broken away. Fig. 2 is a side 15 view, partly in section. Fig. 3 is a broken detail of one of the fillers.

Like letters refer to like parts.

A represents the crate, B the end handles, and C the hinged cover.

20 D is a transverse partition extending from the top to the bottom of the crate and dividing the latter into two parts or receptacles.

Of course the crate may be made of any 25 practical size or may have more than one partition. According to present modes of shipment the receptacles on either side of the partition should be large enough to give room for trays or locked fillers each holding three dozen eggs; but I do not limit myself in this 30 regard nor to the number of fillers.

In filling the crate there is first placed in the bottom of each receptacle a platen E, having spiral springs a depending from the under side and resting on the bottom of the 35 crate. This platen closely fits the walls of the receptacle and obviously acts as a cushion to the weight which may rest upon it or to the jars of transportation. The corner-springs are locked to the central one at b, 40 and the number of them may vary as the case demands. Upon the lower platen is built up a series of egg-filters F, made of cardboard or suitable material and surrounded on all sides by removable strips of corrugated packing-paper h, four of them resting against the 45 walls of the crate. The fillers F vary from

the usual construction by having all their sides locked by a narrow external strip of cardboard c, passing through the projecting tongue d of the strips forming the pockets, 50 as shown. (See Figs. 2 and 3.) When the crate is full, there is placed upon the corrugated paper cover of the upper tray of egg-filters another platen E, constructed like the lower one; but the springs are turned upward, so that when the cover C is closed they will act as a cushion against it for the contents below. (See Fig. 1.)

It will be seen that the eggs are protected on all sides from the jars of transportation and 60 will arrive at commission-houses, &c., in good order; also, that the construction of the crate is simple and economical, and by partitioning, as shown, one crate may be made large enough to hold as much as two separate ones. 65

Having described my invention, what I claim, and desire to secure by Letters Patent, is—

As an article of manufacture, an egg-crate, composed of a body divided into two receptacles by a transverse partition, each receptacle provided with a lower platen having underneath a spiral spring at each corner with its free end locked to a central spiral spring and all of said springs bearing upon 70 the bottom of the crate, a series of egg-filters having their sides locked by a strip c, passing through tongues d of the strips forming the pockets, removable strips of corrugated paper surrounding the egg-filters on all sides, and 80 an upper platen constructed like the lower one and resting upon the packing of the upper egg-filler but having its springs extending reversely to those of the lower platen, and a lid closing down against said springs, 85 as set forth.

Signed by me at Tornado, West Virginia, this 16th day of April, 1898.

ROBERT E. L. GRAY.
